UNITED STATES PATENT OFFICE.

MARTIN T. HANSEN, OF TRENTON, NEW JERSEY.

RAIL-TIE.

1,083,322.

Specification of Letters Patent.

Patented Jan. 6, 1914.

Application filed May 23, 1912. Serial No. 699,310.

To all whom it may concern:

Be it known that I, MARTIN T. HANSEN, a citizen of the United States, residing at Trenton, in the county of Mercer and State 5 of New Jersey, have invented new and useful Improvements in Rail-Ties, of which the following is a specification.

This invention relates to railway ties, and contemplates the provision of a tie for 10 yieldingly supporting the rails, the said tie being formed in sections, one telescoping within the other, and the said sections having an interposed cushion in the form of a spring whereby they are yieldingly connected in order that the upper section may move in relation to the base or lower section.

An object of my invention is to provide a tie of the above-mentioned character in 20 which means are provided for limiting the upper movement of the upper section in relation to the base or lower section.

With the above and other objects in view, my invention relates to such details of construction and in arrangement and combination 25 of the several parts as will be herein-after fully described and specifically pointed out in the appended claims.

In describing my invention in detail, reference will be had to the accompanying drawings wherein like characters denote like or corresponding parts throughout the several views, and in which,

Figure 1 is a longitudinal sectional view 35 of my invention. Fig. 2 is a plan view thereof. Fig. 3 is a cross sectional view, taken on line 3—3, Fig. 1. Fig. 4 is a perspective view of a detail. Fig. 5 is a detailed view.

40 In the accompanying drawings wherein is illustrated the preferred form of my invention, the numeral 1 designates the base or lower section of the tie which is open at its top and has projecting thereinto and 45 from the bottom thereof, studs 2, which studs receive the coil springs 3 and 4, as is obvious, for the purpose of supporting an upper section 5. The upper section is substantially elongated and has side portions 50 bent downwardly at right angles to the body portion as shown at 6, the said sides being adapted to engage the outer sides of the lower section whereby the two sections are held in telescopic engagement with each

other. Lugs 7 also project from the upper section and receive coil springs 3 and 4 so as to prevent their lateral movement.

For purpose of limiting the upper movement of the upper section, members 8 are provided, which members are provided 60 with spaced apart apertures 9 for reception of reinforcing rods 10 and have their upper and lower edges bent inwardly at right angles to the body portion as shown at 11 for engagement with the under side of the 65 lower section and upper side of the upper section;

Here it is readily obvious that the sections are disposed in telescopic engagement with each other and that the upper section 70 is normally held in engagement with the upper inturned end of the member 8 through the medium of the coil springs 3 and 4.

To provide means for fastening the rails 12 to the upper sections grooves or notches 75 13 are provided in the section, which cut out portions are adapted to receive the depending lips 14 of the fastening member 15. The fastening members have formed thereon upwardly extending extensions 16, 80 which are adapted to engage the base flange of the rails in the manner clearly illustrated in the drawings. Any suitable securing means may be provided for fastening the members 15 to the upper section. However, in the drawings I have shown ordinary bolts 17.

It will be readily appreciated that the tie that I have disclosed herein can be manufactured at a very small cost, and that 90 the same is very simple in construction, consists of but a few parts, thereby making its utility obvious.

I desire the greatest of stress to be laid upon the simplicity of my invention, and it 95 is thought that the advantages and novel features of the same will be readily appreciated from the foregoing disclosure.

I desire it to be understood that I may make slight changes in the construction and 100 in the arrangement and combination of the several parts, provided such changes fall within the scope of the subjoined claims.

Having thus fully described my invention what I claim as new and desire to secure by Letters Patent is:—

1. In a device of the character described, a rail tie comprising sections, the lower of

said sections being open at its top, the upper section having its sides bent downwardly for engagement with the sides of the lower section, studs projecting from the 5 base of the lower section, lugs depending from the upper section, coil springs disposed about said studs and said lugs whereby the upper section is held in its uppermost position, clamps engaging the under 10 side of the lower section and the upper side of the upper section whereby the upward movement of the upper section is limited, means extending longitudinally through said lower section for securing said clamps 15 in place, and rail securing means carried by the upper of said sections for the purpose described.

2. In combination with a rail tie comprising two independent sections, the lower 20 of said sections being open at its top, the upper section having its sides bent downwardly to overlap the sides of the said

lower section, the said upper section having a plurality of notches formed therein, studs projecting upwardly from the base of 25 said lower section, lugs depending from the said upper section, springs disposed about said lugs and said studs for normally holding the upper section in raised position, clamping members having their upper and 30 lower edges bent at right angles, said bent portions adapted to overlap the said sections for limiting the movement of the said upper section, rods extending longitudinally throughout the length of said lower 35 section for fastening the said clamping members in place, and rail securing means mounted upon the said upper section of the tie and disposed for engagement with the said notches, as for the purpose set forth.

MARTIN T. HANSEN.
